DESIGN FOR A BADGE

Benjamin E. Neal, Los Angeles, Calif.

Application January 9, 1942, Serial No. 105,094

Term of patent 3½ years

To all whom it may concern:

Be it known that I, Benjamin E. Neal, a citizen of the United States, residing at Los Angeles, in the county of Los Angeles and State of California, have invented a new, original, and ornamental Design for a Badge, of which the following is a specification, reference being had to the accompanying drawing, forming part thereof.

In said drawing:

Fig. 1 is a front elevational view of a badge, showing my new design, and

Fig. 2 is a top plan view thereof.

I claim:

The ornamental design for a badge, as shown.

BENJAMIN E. NEAL,
